UNITED STATES PATENT OFFICE.

HARRY JONES, OF STERLING, ILLINOIS.

PUMP.

SPECIFICATION forming part of Letters Patent No. 245,835, dated August 16, 1881.

Application filed December 31, 1880. (Model.)

To all whom it may concern:

Be it known that I, HARRY JONES, of Sterling, in the county of Whiteside and State of Illinois, have invented certain new and useful 5 Improvements in Pumps; and I do hereby declare that the following is a full, clear, and exact description of the invention, which will enable others skilled in the art to which it appertains to make and use the same, reference 10 being had to the accompanying drawings, which form a part of this specification, and in which—

Figure 1 is a vertical section of my double-acting force-pump, and Fig. 2 is a section of the stationary plunger on an enlarged scale.

15 Similar letters of reference indicate corresponding parts in all the figures.

My invention has relation to double-acting force-pumps of that class in which two stationary plungers operate in conjunction with two 20 vertically-reciprocating buckets; and it consists in the improvements hereinafter more fully described, and particularly pointed out in the claims.

In the annexed drawings, A indicates the 25 pump stock or barrel, made of wood or metal, having a spout or outlet, a, and a lever-handle, B, with its fulcrum at b. This barrel (which may be of any suitable length and made in a simple and inexpensive way by coupling several lengths of gas-pipe or ordinary water-pipe) 30 is set at its lower end into a tubular cross-piece or barrel, C, which has two projecting studs, c c, one at each end. Into the ends of, or cast in one piece with, the horizontal barrel C are 35 inserted the plunger-pipes D D, to the lower ends of which are affixed the stationary plungers E. By reference to Fig. 2 of the drawings it will be seen that each of these plungers is constructed with a concave seat for the 40 ball-valve d, which plays in its chamber e.

ff are ducts which open from the chamber e to the outside of the plunger-cylinder. The outer ends of these ducts are slightly concaved or funnel-shaped, as shown in the drawings, the 45 body or head of the plunger proper being cylindrical in shape and provided with two circumferential grooves or channels, g g, equidistant from, and one above and the other below, the circumferential ducts or outlets f. Into these 50 channels may be inserted leather or rubber packing h, there being no packing between said channels.

F F are the pump-buckets, which are cylindrical in shape to fit the plungers, open at the top and with an aperture in the bottom closed by a ball-valve, i. To the top of each of the buckets is hinged the bifurcated lowermost section of its appropriate sucker-rod G, there being a sufficient number or lengths of these rods, coupled together by couplings H, to reach up to the lever B, by which the pump is operated.

In using this pump in cisterns or reservoirs, where it is desirable to stir the water and keep it in motion to prevent sediment, I provide each section of the immersed portion of the 65 sucker-rods with laterally-projecting wings or flanges m, which will have the desired effect. The reciprocation of the buckets themselves, working up and down upon their respective plungers, also has the effect to agitate the water in the well or cistern much more effectually than where the cylinder is stationary and the plunger reciprocates within it.

If, by any accident in coupling or disconnecting the sucker-rods, one of the sections should 75 slip and fall, it will not fall, with its bucket, to the bottom of the well, but will be caught upon the projecting stud or arm c on its side of the cross-barrel C, from which it can readily be lifted up and coupled in its appropriate 80 place. These studs or arms, by projecting laterally out over the rim of the buckets, also form guards or abutments against the sides of the well or well-tube, so that the buckets will 85 swing easy and have free play up and down without friction against the sides.

By the construction of the plunger in the manner described a jet of water is on each upward stroke of the bucket forced through the ducts f, and escapes in an upward and downward direction between the wall or sides of the bucket and the upper and lower annular elastic packing, h, thereby thoroughly washing out grit, gravel, and other impurities that find their way in between the packing and the bucket, and which, if not removed, is apt to cut and otherwise injure the packing. The funnel-shaped mouths or outlets of the ducts f facilitate this operation by forming the water into a narrow sheet, which will easily work 90 in between the bucket and the plunger-packing.

This pump is adapted to all purposes where it is desired to obtain a strong and steadily,

flowing stream under pressure. It may be used in shallow reservoirs or in deep wells with equal advantage; is strong, durable, and not liable to get out of order, and may be used in gritty or 5 muddy water without becoming choked up or causing injury to its parts.

Having thus described my invention, I claim and desire to secure by Letters Patent of the United States—

- 10 1. In a double-acting pump of the described class, the bifurcated pump-stock A C, provided at its lower forked end with the laterally-projecting guard-studs or abutments e e, substantially as and for the purpose shown and set 15 forth.

2. The hollow plunger E, of cylindrical shape, provided with the valve d, upper and lower circular packing-channels, g g, and intermediate concaved ducts or outlets, f, substantially as and for the purpose herein shown and specified.

In testimony that I claim the foregoing as my own I have hereto affixed my signature in presence of two witnesses.

HARRY JONES.
